Primary Examiner — Ralf Seifert*(74) Attorney, Agent, or Firm* — Howard Eichenblatt(57) **CLAIM**

The ornamental design for an ornamental necktie device, as shown and described.

DESCRIPTION

FIG. 1 is a front perspective view of a first embodiment of an ornamental necktie device showing my new design;
FIG. 2 is a front view thereof;
FIG. 3 is a back view thereof;
FIG. 4 is a left side view thereof;
FIG. 5 is a right side view thereof;
FIG. 6 is a top view thereof; and,
FIG. 7 is a bottom view thereof.
